UNITED STATES PATENT OFFICE.

ARTHUR O. GRANGER, OF PHILADELPHIA, PENNSYLVANIA.

GAS-GENERATING APPARATUS.

SPECIFICATION forming part of Letters Patent No. 311,484, dated February 3, 1885.

Application filed June 25, 1883. (No model.)

To all whom it may concern:

Be it known that I, ARTHUR O. GRANGER, of the city of Philadelphia, county of Philadelphia and State of Pennsylvania, have invented an Improvement in Gas-Generating Apparatus, of which the following is a specification.

My invention has reference to apparatus for manufacturing illuminating or heating gas; and it consists more specifically in certain improvements in the generator, fully set forth in the following specification, and shown in the accompanying drawings, which form a part thereof.

15 Heretofore water-gas has been made in comparatively small generators or gasogenes, their area being limited by the ability of the grate to support the weight of the bed of coal.

The object of my improvement is to so construct a generator as to contain many times the quantity of coal ordinarily found practicable, and so produce, with but little extra labor, a very large increase in the volume of gas in a given time.

25 In the drawings, Figure 1 is a sectional elevation of my improved generator on line *x x*. Fig. 2 is a sectional plan view of same on line *y y*, looking upward. Fig. 3 is also a sectional plan of same on line *z z*, looking down; 30 and Fig. 4 is an elevation showing a full gas-works.

A is the generator. B is the superheater; and D', the seal or washer, the two latter of which may be constructed in any of the well-known ways.

35 The generator A may be made, say, thirteen feet internal diameter, and have vertical or slightly conical walls, the diameter being greatest at the bottom. The ash-pit M below the grate-bars E' is divided by a fire-brick wall, D, having pressure-equalizing apertures K through it, so that the air and steam may circulate between the two compartments of said ash-pit if there should be any difference 40 in pressure or resistance offered to the passage of air or steam by the bed of coal. The inner ends of the grate-bars E' rest on the wall D, and the outer ends rest on beams or bars E, which are supported by iron posts F in the 45 center and by the lining-wall at their ends.

In order to clean the fire, I provide two sets

of double doors, S, similar to those patented to myself and Collins, May 1, 1883, on opposite sides of the generator and parallel to the wall D. These four doors S', on each side, when 55 open, swing upon hinges S², and expose the entire width of grate, as seen in Fig. 3, and leave it exposed on opposite sides of the generator, making a perfect cleaning possible.

The roof or dome of the generator is made 60 of fire-brick, and is made of a series of three groined arches. The arches C are first built and then the curved parts C' built in. This dome is pierced with three coaling-openings, A', having gas-tight lids, and three or more 65 cleaning or stoking holes, R, also covered with gas-tight lids or covers.

A² is the gas-outlet, and connects with the superheater B. It opens from between two of the arches C, as in the case of the coaling- 70 openings A'. Air is admitted at four places below the grate-bars by nozzles G', which open from a central pipe, G, and the blast to all nozzles may be regulated by a single valve, G². Steam is admitted under the grates through 75 two openings, H, a single valve, I, controlling the supply to both openings.

In order to utilize heat that is now usually wasted and to superheat the steam, I place a coil of pipe, O, back of the fire-brick lining. 80 The steam from the boiler enters the said coil at the top part, which may be supplied with a valve, N, and is led outside the generator-case by bent pipe O', from which the two nozzles P P spring and enter openings H, the 85 valve I being located in said bend O', as shown in Fig. 1.

I am aware of the patents to Springer, No. 263,612, of 1882, and Stanton and Hutchinson, No. 203,666, of 1878, and claim nothing 90 therein set forth or shown.

Having now described my invention, what I claim as new, and desire to secure by Letters Patent, is—

1. In a gas-generator, a grate of large area 95 and unobstructed from above, in combination with the ash-pit, a dividing-wall having one or more open passages through the same and supporting the said grate diametrically across its center, air and steam pipes opening into said 100 divided ash-pit and on each side of said dividing-wall, and cleaning-doors arranged up-

- on diametrically-opposite sides of the grate at right angles to the dividing-wall, substantially as and for the purpose specified.
2. In a generator, a grate of large area and 5 unobstructed from above, in combination with the ash-pit, a dividing-wall having one or more open passages through the same, and supporting the said grate diametrically across its center, air and steam pipes opening into 10 said divided ash-pit and on each side of said dividing-wall, and cleaning-doors arranged upon diametrically-opposite sides of the grate and at right angles to dividing-wall, and of sufficient height to expose the space above 15 the grate as well as the ash-pit, substantially as and for the purpose specified.
3. In a gas-generator, a grate of large area and unobstructed from above, in combination with an ash-pit, a dividing-wall having one 20 or more perforations and supporting said grate diametrically across its center, posts F, and supporting-bars E, substantially as and for the purpose specified.
4. A gas-generator of large diameter provided with cleaning-doors consisting of four 25 doors, S', hinged, as shown, to form a set on a level with the grate and ash-pits and on opposite sides thereof, the said doors when open exposing the entire width of grate and ash-30 pit or full internal diameter of the generator, substantially as and for the purpose specified.
5. A gas-generator of large diameter provided with cleaning-doors on a level with the 35 grate and ash-pits and on opposite sides thereof, in combination with grate E', supporting-bars E, dividing-wall D, and blast-pipes, substantially as and for the purpose specified.
6. A gas-generator of large diameter pro-
- vided with cleaning-doors on a level with the 40 grate and ash-pits and on opposite sides thereof, in combination with grate E', supporting-bars E, perforated dividing-wall D, and blast and steam pipes, substantially as and for the purpose specified.
7. A gas-generator of large diameter provided with a groined arch dome or roof consisting of arches C C', and coaling-holes through 45 said arches C' between the arches C, substantially as and for the purpose specified.
8. A gas-generator of large diameter provided with a groined arch dome or roof consisting of arches C C', and coaling and stoking holes through said arches C' between the arches C, substantially as and for the purpose specified.
9. A gas-generator of large diameter provided with a groined arch dome or roof consisting of arches C C', coaling and stoking holes, and exit gas-flue through said arches C' 50 between the arches C, substantially as and for the purpose specified.
10. In a gas-generator, the combination of the grate, ash-pit, dividing-wall for said ash-pit, a single blast-pipe, G, provided with a valve, G', and a series of blast-nozzles, G', 55 also opening from said blast-pipe, arranged to face the grate-bars, and substantially equidistant from each other, substantially as and for the purpose specified.

In testimony of which invention I hereunto 70 set my hand.

ARTHUR O. GRANGER.
